UNITED STATES PATENT OFFICE.

PAUL BROWN KLUGH AND AURA E. WHITEHEAD, OF CHICAGO, ILLINOIS,
ASSIGNORS TO THE CABLE COMPANY, OF CHICAGO, ILLINOIS, A COR-
PORATION OF ILLINOIS.

AUTOMATIC WEB-GUIDING DEVICE.

No. 832,932.

Specification of Letters Patent.

Patented Oct. 9, 1906.

Application filed August 10, 1905. Serial No. 273,638.

To all whom it may concern:

Be it known that we, PAUL BROWN KLUGH and AURA E. WHITEHEAD, citizens of the United States, residing at the city of Chicago, in the county of Cook and State of Illinois, have invented certain new and useful Improvements in Automatic Web-Guiding Devices, of which the following is a specification.

Our invention relates to devices for automatically guiding note-perforations in sheets or webs during progress over rolls in accurate relation to orifices intermediate of the rolls and for constantly testing this accuracy and correcting any tendency of the sheet to draw the perforations out of such relation.

The object of the invention is to obtain this automatic guidance and correction from the perforations and interstices independently of the edges of the web or sheet, to counteract the effects thereon of atmospheric conditions, to provide capacity for numerous correction-points so arranged that no special arrangement or alinement of the perforations will be necessary, and to avoid wrinkling the web or sheet when returning the perforations to their normal path.

In our preferred form the device consists in general of feed or rewind rolls and take-up or wind rolls having capacity for longitudinal adjustment along their axes, a sheet traveling from one to the other and having at intervals on its surface small perforations, fixed slits or apertures intermediate of the rolls covered during normal progress of the sheet by the imperforate or intervening portions and arranged so near the edges of the perforations that deflection or divergence from the normal path will expose them through the perforations and set in operation pneumatically-controlled levers and springs for shifting the rolls simultaneously in opposite directions to cover the slits, thus returning the web to its normal path and suspending the operation of the shifting mechanism until exposure again occurs, when the operation is repeated. By these means a very delicate and nice adjustment of the perforations themselves in relation to the slits is had.

The device is especially adapted for guiding the perforated note-apertures of note-sheets in accurate registration with tracker-bar orifices of self-playing musical instru-

ments, wherein the note-apertures are intended to travel in registration with corresponding tracker-bar orifices connected by tubing with exhaust-chests and sound-producing devices, well known in this art and therefore not here shown. Any of the standard note-sheets having the usual perforations adapted to operate such mechanism in proper sequence for playing a tune may be used without cutting special perforations for the guiding mechanism or otherwise specially preparing the music-sheet for use with our device.

In applying our device to the guidance of perforated note-sheets it is desirable that each perforation as it passes the tracker-bar region should be in accurate alinement for perfect registration with the proper tracker-bar orifice. In our device where there is any failure on the part of a perforation or set of perforations to register accurately with the corresponding tracker-bar orifices one or more of a plurality of slits or trigger-openings each positioned in the tracker-bar out of registration with the tracker-bar orifices and on the edge of the normal path of the corresponding note-perforation and normally covered by the interstices or intervening spaces about the perforations will become exposed, admitting air through the perforations into tubes and mains arranged to operate pneumatics and set in operation the roll-shifting mechanism connected thereto, thus guiding the sheet in the direction required for perfect registration of the perforation and tracker-bar orifices and closure of the slits and connected tubes.

The outer edges of note-sheets and other fragile fabrics, even when cut straight originally, are subject to so many variations that their use as a guiding-line for shifting mechanism depending for satisfactory operation on their straightness and regularity is objectionable. They expand or contract with changes of atmospheric conditions, curl or turn from the results of changes in temperature and from frequent winding and rewinding, and are more exposed to wear or injury than the interior portions of the paper. The contraction and expansion renders it impossible to obtain the desired delicacy of correction or adjustment, since to allow for contraction it is necessary to place the operat-

ing-slit back some distance under the edge, while expansion may seriously interfere with accurate registration. So, too, the curling or fraying of the edges would destroy delicacy of correction and interfere with satisfactory operation in a device which depends upon the outside edges for correction, since obviously a curled, turned, or defective edge will admit air to the slits or trigger-apertures during normal progress, and thus defeat the object of the shifting mechanism. These objections are obviated in the present invention by deriving the guidance from the intervening paper between the perforations so positioned as to pass near the edges of the perforations, which edges being very short and protected by the surrounding paper cannot appreciably curl or turn and are less likely to present irregularities, while the use of a number of correction-points insures constant test and frequent correction. Our invention is also adapted to guide sheets having biased, crooked, or jagged edges. Our device has capacity for guiding sheets perforated at any point or points intermediate of the edges, no special alinement, preparation, or arrangement of the perforations thereon being necessary.

Inaccuracy in the perforating of note-sheets due to divergence of the sheet from its normal path when being fed to a music-cutting machine results in a variable margin in relation to the edge of the sheet. Our device has capacity for correcting this defect in manufacture.

Further, there is an objection to moving one roll and adjusting it relative to the other, since it is apt, especially in very fragile fabrics, to cause the sheet to wrinkle. This difficulty is overcome in the present invention by mechanism which alines both rolls simultaneously.

In the accompanying drawings we have shown a device embodying our invention in its preferred form, illustrating its use on self-playing musical instruments.

Figure 1 is a face view of a frame containing feed or rewind and take-up or wind rolls and mechanism for shifting them laterally in either direction, the perforated sheet or web thereon being cut away to reveal the tracker-bar orifices and the slits or trigger-openings operating the shifting mechanism. This figure shows the position assumed by the parts when the sheet is in its normal path of travel, the approaching perforations being in proper alinement for accurate registration with the orifices. Fig. 2 is a similar view of the tracker-bar and adjacent parts, showing the position assumed by a perforation when the sheet is diverted or deflected from its normal path too far to the right, so that the perforation exposes one of the slits or trigger-openings and fails to register accurately with the corresponding tracker-orifice. Fig. 3 is

a face view of the pneumatics for operating the shifting-rod to adjust the rolls and of the tube connections between the slits or trigger - openings and the pneumatics. The pneumatics are here shown in the position assumed when the sheet is traveling in its normal path. Fig. 4 is a front view of the pneumatics, showing the position assumed when the sheet has been deflected from or drawn out of its normal path too far to the right. Fig. 5 is a cross - section of the feed and take - up rolls and tracker - bar, showing in perspective the tubes connecting the slits with the main conduits or pipes to the pneumatics and a tracker-bar orifice with the connecting-tube to sound-producing devices. Fig. 6 is a top view of a portion of the tracker-bar, showing the relative location of the slits and tracker-bar orifices. Fig. 7 is a cross-section on the line 7 of Fig. 6. Fig. 8 is a similar view taken on the line 8 of Fig. 6. A indicates any suitable frame for take-up roll B and delivery or music roll C, suitably mounted on shafts 1 and 2, laterally slidable in bearings 29 and 30. 4 indicates the sheet and 5 the perforation therein.

D is the tracker-bar, having the usual orifices 3. Adjacent to these orifices, but out of alinement with them, are pairs of slits or mouthpieces 6 and 7, 6 opening into tubes 8, 95 communicating through main 11 with collapsible pneumatic 12, and slits or mouthpieces 7 into tubes 9, communicating through main 10 with collapsible pneumatic 14. The tracker-tubes and mains are exhausted of air when covered by the sheet by bleeder or exhaust mechanism well known in this art. We prefer to provide as many of these slits as there are spaces between the tracker-bar orifices, though it is obvious that fewer pairs may be used to advantage when desired. It will be noticed that the slits 6 are arranged in the normal path of the web to pass under the left-hand margins of the perforation and 7 under the right-hand margins. We prefer to arrange 6 and 7 alternately across the path of the perforations, 6 operating to shift the sheet to the right and 7 to the left, and to accomplish this shifting by attaching to pneumatic 12 the lever 15, loosely embracing the rod 16, rigidly securing the rod 16, the button 17 having cushioned surface or surfaces 18 so positioned that the contraction of collapsible pneumatic 12 will cause the lever 15 to contract with it and draw rod 16 from left to right, and similarly attaching to collapsible pneumatic 14 the lever 19, loosely embracing rod 16, adapted, when the pneumatic 14 is collapsed, to contact with the cushioned surface 18^a of the button 17^a, rigidly secured to rod 16, thus thrusting the rod from right to left.

Attached to the frame A, Fig. 1, are horizontal supports 20 and 21, holding the upright shaft 22. Shaft 22 at its lower end is bent at right angles, and to the end of this

horizontal member is connected the rod 16. By shifting rod 16 shaft 22 may be rotated. Shaft 22 is provided with arms 23 and 24. Arm 23 bears on the outer or right-hand side 5 of the abutment or collar 25, rigidly secured to shaft 2, and arm 24 on the inner or left-hand side of collar 26 on shaft 1. When arm 23 is actuated to move the upper roll C to the left, arm 24 moves roll B until the collar contacts with spring 27, thus placing the rolls B and C in alinement. Likewise when arm 24 is actuated to move the lower roll B to the right arm 23 moves away from collar 25, allowing spring 28 to move the upper roll C 15 until collar 25 contacts with arm 23, likewise placing the rolls B and C in alinement.

While we have shown and described mechanism in which the normal relation between the note-perforations and tracker-orifices is 20 maintained or restored by shifting the sheet or web, we do not wish to be understood as limiting our invention to this construction, but

What we claim, and desire to secure by Letters Patent, is—

1. The combination of a traveling sheet or web provided with perforations adapted to operate sound-producing devices in proper sequence for playing a tune, and means for 30 propelling it, with means, covered by the sheet or web during normal progress and exposed through a playing-perforation by divergence of the sheet therefrom, for restoring it to that normal position.

2. The combination with a sheet or web having perforations irregularly disposed across it, of wind and rewind rolls, and means, contacting with the right and left margins of the perforations held out of operation 40 when the perforations are in normal position, for shifting said rolls simultaneously to restore the perforations to normal position when diverted therefrom.

3. In combination with a sheet or web having playing-perforations disposed at intervals across its surface, means for propelling it, ducts beneath the sheet contacting with and closed by the imperforate portions of the sheet when the sheet is in normal position, and means, set in operation by exposure of a duct through a playing-perforation, for restoring contact between the ducts and imperforate portions of the sheet when the sheet is diverted from said normal position.

4. The combination with a sheet or web having perforations adapted to operate mechanical musical instruments in proper sequence for playing the same, of means contacting with the margin of a playing-perforation held out of operation when the perforation is in its normal position, for restoring it to that normal position when diverted therefrom.

5. The combination of a sheet provided 65 with playing-perforations and tracker-bar

orifices normally registering therewith, with pairs of trigger-orifices covered during registration by opposite margins of the playing-perforations, some of said perforations being out of longitudinal alinement with others on 70 said sheet, and mechanism adapted to be operated by said trigger-orifices to shift the sheet to cover them and return the perforations when deflected therefrom to registration with said tracker-bar orifices.

6. In combination with a tracker-board, a sheet having perforations arranged thereon in proper relation for playing a tune, means for propelling it over the tracker-board and means covered by the sheet during normal 80 progress and exposed through one or more of said perforations by divergence of the sheet therefrom for restoring it to that normal position.

7. The combination with a traveling sheet 85 containing a plurality of lines of playing-perforations and tracker-bar orifices adapted to register with each line, with pairs of trigger-apertures in said tracker-bar arranged in alinement with the spaces between said orifices, said apertures being covered during registration of the perforation and tracker-orifice by the opposite margins of the perforation and uncovered by failure of such registration, and means for shifting said sheet to 95 cover the apertures and correct said registration.

8. The combination of a sheet or web having a plurality of lines of playing-perforations with a plurality of right and left ducts 100 or channels opening beneath the sheet and normally closed by the imperforate portions thereof, and shifting mechanism, operation of which is inaugurated by exposure of said ducts through a playing-perforation, for restoring the normal registration between said imperforate portions and said ducts.

9. The combination with a traveling sheet having perforations adapted to operate player mechanism in proper sequence for 110 playing a tune, of tracker-bar orifices, and means, maintained in inoperative condition by the interstices between and marginal edges of the perforations when the latter are registering correctly with said orifices, for restoring correct registration when uncovered by a perforation.

10. The combination with a sheet having a plurality of lines of note-perforations thereon, of pneumatically-operated mechanism for 120 shifting the sheet from side to side, and tubes, the open ends thereof contacting with the sheet, adapted to hold said mechanism out of operation during contact with the imperforate portions of said sheet, and operate 125 it on contact with a note-perforation to shift the sheet laterally and cover said tubes with the imperforate portions of the sheet.

11. In combination with a fixed tracker-board, a traveling perforated note-sheet,

means for propelling it over the mouths of the tracker-board, and mechanism, set in operation by the note-perforations, for moving the rolls longitudinally in their bearings.

5 12. The combination of wind and rewind rolls movable longitudinally in their respective bearings, with a sheet adapted to travel thereover, provided with a plurality of lines of note-perforations at various points across it, tubes having an open end contacting with said sheet adapted to operate pneumatics, and connections between said pneumatics and the shafts of said rolls, whereby exposure of said tube end through a note-perforation 10 operates said pneumatics to shift said rolls and sheets to cover the tube end for the purposes described.

13. The combination of a sheet or web having perforations arranged thereon in proper relation for playing a tune, with rolls, by which it is propelled mounted on longitudinally-movable shafts, tubes alternately sealed by the imperforate and opened by the perforate portions of said sheet, some of said 20 perforations being out of longitudinal alignment with others, a pair of pneumatics adapted to be operated by the admission of air through said tubes, a rock-shaft supported transversely of said roll-shafts, abutments on 25 said roll-shafts, two lever-arms on said rock-shaft the first adapted to contact with one of said abutments on one side and the second with the other on the opposite side, springs adapted to hold said arms and abutments in 30 contact, and connections for rotating said 35

rock-shaft in one direction on collapse of one pneumatic and in the opposite direction on collapse of the other, each pneumatic being connected with alternate tubes.

14. The combination of a web or sheet 40 having perforations therein arranged in proper relation for playing a tune, rolls mounted on longitudinally-movable shafts, and means for winding said sheet or web from one roll to the other, with pneumatics collapsible in opposite directions, tubes contacting with said sheet or web alternately covered by the imperforate and uncovered by the perforate portions of said sheet or web, connections from alternate tubes to the same pneumatic, rod connections to said pneumatic adapted to move in one direction on collapse of one pneumatic and in the other direction on collapse of the other, a rock-shaft supported 45 transversely of said roll-shafts and rotated by said rod, said rock-shaft having lever-arms adapted to contact with the ends of said roll-shafts and move one in one direction and the other in the other direction according to said rotation, and springs adapted to 50 hold said roll-shafts and lever-arms in contact.

In testimony whereof we hereunto affix our signatures in presence of two witnesses.
